UNITED STATES PATENT OFFICE.

DAVID BOURQUE, OF AMESBURY, MASSACHUSETTS, ASSIGNOR TO G. W. J. MURPHY COMPANY, OF AMESBURY, MASSACHUSETTS, A CORPORATION OF MASSACHUSETTS.

WINDOW CONSTRUCTION.

1,392,243.

Specification of Letters Patent. Patented Sept. 27, 1921.

Application filed May 29, 1918. Serial No. 237,332.

To all whom it may concern:

Be it known that I, DAVID BOURQUE, a citizen of the United States, and resident of Amesbury, in the county of Essex and State 5 of Massachusetts, have invented an Improvement in Window Construction, of which the following description, in connection with the accompanying drawings, is a specification, like characters on the drawings representing 10 like parts.

This invention relates to window constructions and the purpose is to provide an improved device whereby the adjustment of a window is facilitated.

15 While my invention is of general application, I have for purposes of illustration here shown it as applied to a window as ordinarily placed in the door of a closed vehicle such as a limousine.

20 The construction and operation of my device will best be understood by the following description of the particular embodiment illustrated in the accompanying drawings wherein:—

25 Figure 1 is a vertical section of the door frame of a motor car or similar vehicle, viewed from the inner side, and showing the window proper and its operating mechanism in elevation;

30 Fig. 2 is a section with the operating handle omitted and most of the door frame broken away, the remaining parts being shown substantially along the line 2—2 of Fig. 1;

35 Fig. 3 is a section on the line 3—3 of Fig. 1; and

Fig. 4 is a section on the line 4—4 of Fig. 2.

Referring to the drawings, I have shown 40 in Fig. 1 a portion of a door 5 of the type customary in vehicles provided at an intermediate point in its height with a sill 7 defining thereabove a window frame 9 having an opening which is adapted to receive 45 the light or window proper 11. Herein the window proper consists of a single light or sheet of glass. However, it might have a number of lights and be mounted in a sash. I shall herein use the word light to distinguish the window proper from the window 50 including the frame in which it is mounted. When the light is raised it closes the open-

ing above the sill 7 and when it is lowered it sinks beneath the sill and is housed within the lower part of the door. The light is 55 guided in its movement in suitable guides at the side of the frame which will be hereinafter more fully described. For the present I shall disregard their structure and will proceed to a description of the manner 60 in which the light is raised and lowered in the embodiment of the invention shown.

Referring to Fig. 1, in the present instance the major portion of the weight of the light is counterbalanced by means of the spring 65 13 which is attached to lever 15, which lever carries a roller 17 which runs on a strip 18 (Fig. 2) secured to the bottom edge of the light. The lever 15 swings clockwise, tensioning the spring as the light is lowered 70 and the spring swings it counterclockwise again as the light is raised.

In the example of my invention here illustrated, the window is operated by a lever 19 which moves crosswise of the window and 75 has a handle 21 presented adjacent the sill of the same. This lever by means of the bell crank 23 is adapted to work the lazy tongs 25 which carry at their upper end the pin 27 passing loosely through the strip 18. Referring to Fig. 1, it will be understood that if the handle 21 is swung to the left along the window sill, the lazy tongs 25 will be collapsed and the light will be lowered and movement in the opposite direction will extend the tongs and lift the light. Because 80 of the counterbalance provided by the spring 13, but little force is required to operate the lever 19.

In the embodiment of my invention here 90 shown I have provided means whereby the light is firmly held in its various positions of adjustment, whereas it may be freely moved when it is desired to raise and lower the same. For this purpose the guides in 95 which it slides are adapted to grip the same. Referring particularly to Fig. 2, I have here shown the guides as including upper and lower channels adapted to receive the light in its lowered and raised positions, respectively. Herein the lower guide consists of two angle bars, a relatively fixed angle bar 29 pivoted at 30 adjacent its lower end and a relatively movable angle bar 31 hav-

ing a flange overlapping a flange of the bar 29 (see Fig. 4). The overlapping flanges are joined by means of rivets 33 which are received in diagonal slots 35 in the movable bar 31. There is thus provided an expandable channel and if the movable angle bar 31 is longitudinally shifted, its outwardly projecting flange will be brought correspondingly nearer to or farther away from the opposite flange of the bar 29 according to the direction of movement. The upper channel guide comprises a similar relatively fixed angle bar 29^a, pivoted at 30^a (Fig. 1), and the angle bar 31 is continued to provide the other half of the upper channel. However, the overflapping flange of the angle bar 31 is cut away between the bars 29 and 29^a so that the two end portions of the angle bar 31 corresponding to the two expandable channel guides are connected solely by a laterally yieldable strip of metal 37. Normally, the two channels will be alined in the line between the pivot 30 and the corresponding upper pivot 30^a, but the yielding connection between the same, which in the present instance is provided for by an integral extension of the parts at 37, permits disalinement as shown in an exaggerated manner in Fig. 2. The purpose of this will appear more fully hereinafter.

I preferably provide means whereby the expandable channels are normally collapsed into gripping relation to the edges of the light 11. For this purpose springs 39, (Figs. 2 and 3), may be attached at either side of the window to projections 41 from the movable angle bars 31, these springs being attached to suitable fixed points on the body of the door. By this means each bar 31 is drawn downwardly, and because of the inclination of the slots 35, as shown in Fig. 2, the outwardly projecting flanges thereof will be crowded over toward the outwardly projecting flanges of the bars 29 and 29^a and into gripping relation to the edges of the light 11. The light 11 frictionally engaging the inner side of the flanges will further tend to thrust the angle bars 31 downwardly and will thus wedge the same into gripping relation to itself.

By the construction just described the light is firmly held and cannot rattle or shift its position of itself. When it is desired to move the same, the guiding channels are spread by shifting the angle bar 31 upwardly against the tension of the springs 39. For this purpose I have herein provided a pair of arms 43 mounted on a rock shaft 45 and engaging projections 47 from the angle bars 31 at opposite sides of the window, respectively. Herein (see Fig. 2) a thrust element 49 is adapted to engage one of the arms 43 and lift the same, and the shaft 45 will thereby be rocked and the opposite arm shown in Fig. 3 will also be

operated. Preferably, this thrust member is controlled by a suitable finger grip associated with the operating handle 21 so that the guiding channels may be expanded and their grip on the light relaxed by the action of the fingers of one hand preparatory to movement of that hand to raise or lower the light. Referring to Fig. 2 and then to Fig. 1, the thrust member 49 as herein shown consists of a wire held against kinking by a casing 51 and this wire is extended to a position adjacent the handle 21 where it is secured to a block 53 which may be depressed by pressure on the plunger 55 which projects in the manner of a button at the top of the handle 21. A spring 57 normally lifts the plunger and thus draws on the wire 49 and since it is held to shape by the casing 51 the projecting end is withdrawn from the arm 43 (Fig. 2), permitting the springs 39 to draw the angle bar 31 downwardly. When the plunger 55 is depressed, the wire 49 will thrust the arm 43 upwardly and, lifting bars 31 against the force of springs 39, spread the flanges of the channel guides and release the light for movement upwardly or downwardly by means of the lazy tongs 25 actuated by the swinging lever 19.

I shall next describe the manner in which the light is held in elevated position and the manner in which it is disengaged preparatory to lowering. To hold the light in its raised position, it is displaced laterally and supported by the sill 7. Referring to Fig. 2, I have there shown the lower edge of the light inclosed in a metal strip 59 which at the outside is turned over to form a downwardly facing hook or channel 61 which is adapted to fit over a projecting ridge 63 on the sill 7. It will be apparent from Fig. 2 that when the upper and lower channel guides are in alinement, the outer end of the hook will clear the sill 7 and its ridge 63, but if the light is displaced to the left, as is possible because of the yielding character of the part 37 and the pivoting of the guides, the channel may be moved over the top of the ridge 63 and lowered to engage the same. The light will then be securely held in the position shown in Fig. 1 and the engaging portions will provide a seal preventing the entrance of water.

Herein I have shown means for automatically moving the light over toward the sill 120 as it is raised by movement of the lever 19. For this purpose an arm 65, which may be somewhat resilient, is here shown as extending from the lower edge of the light, which arm is provided with an offset portion 67 (Fig. 1) which forms a follower adapted to coöperate alternatively with the diagonal cam surfaces 69 and 71 of a diagonally disposed plate supported by a resilient arm 73 from a part of the door. 130

Either or both of the arms 65 and 73 may be more or less resilient.

Let us suppose that the light is in lowered position and that it is lifted by swinging the lever 19 in a clockwise direction over toward the position shown in Fig. 1. Viewing Fig. 2, as the lower edge of the light approaches the sill 7 and has left the lower guide, the offset follower 67 will come in contact with the diagonal surface 69 and as the lifting is continued the light will be yieldingly pressed over toward the sill until the bottom of the channel 61 clears the top of ridge 63 when it will snap over the same. This action will be apparent to the operator who can then release handle 21 and the light will drop by gravity into the position shown in Fig. 2. The yielding pressure of the offset 67 against surface 69 due to the resiliency of one or both of the arms 65 and 73 will, in coöperation with the gripping channels, hold the light snug and prevent any rattling.

If it is desired to lower the window, the handle is given a slight movement clockwise to raise the light from the position shown in Fig. 1, so that the channel 61 clears the ridge 63. By this movement the follower portion 67 will be brought above the end of surface 69. The tendency of the yielding connection 37 between the two guides is to bring them into alinement and thus to move the light to the right, viewing Fig. 2, so that the channel will be clear of the ridge. This is permitted because of the release of the spring pressure between the parts 67 and 69. Because of the resilient nature of one or both of them the arm 73 may spring to the left or the arm 65 to the right. In either event the position of the parts is such that if the lever 19 is now moved anti-clockwise to lower the light through the action of the lazy tongs 25, the follower 67 will now come in contact with the diagonal surface 71 which, reinforcing the action of the part 37, will draw the same to the right viewing Fig. 2, thus making certain that the parts 61 and 63 will not engage but that the light may be lowered past the sill and into the lower channel guide. By this means the edge of the light is, as it were switched to and from the sill in raising and lowering the same, respectively.

I have described in detail the particular embodiment of my invention shown in the accompanying drawings. Obviously, while the complete combination of elements described is most desirable, certain of them might be used independently of the rest or with similar devices of a like nature. The exact mechanical embodiments of the principles of my invention chosen for purposes of illustration may also be considerably varied without departing from the scope of

my invention as defined in the following claims: —

1. In a window construction, a light, fixed angle bars each having a flange presented to one side of the light to guide the same, angle bars having flanges connected to other flanges of said fixed bars for relative diagonal movement whereby to provide spreadable channel guides and means for longitudinally shifting said latter bars. 75

2. In a window construction, a light, fixed angle bars each having a flange presented to one side of the light to guide the same, angle bars having flanges connected to other flanges of said fixed bars for relative diagonal movement whereby to provide spreadable channel guides, spring means for normally longitudinally moving said latter bars to effect lateral movement of the same into clamping relation to the light and manually operable means for moving the bars against the action of said spring means. 80

3. The guide for a window or light comprising an angle bar having a flange cut away between its ends and shorter angle bars connected to said flange for relative diagonal movement and providing spreadable channel guides. 90

4. In a window construction, a light, fixed guides and opposed relatively movable guides receiving between them the edges of the light, said movable guides being arranged for movement toward and from said fixed guides on longitudinal movement relative thereto, a rock shaft, arms thereon engaging said movable guides, springs associated therewith, a handle for lifting and lowering the light, a finger grip associated therewith and means controlled by said finger grip for operating said shaft against the springs. 100

5. In a window construction, a light, guides engaging the edges of the light and mounted for diagonal movement, means for exerting a longitudinal force on the guides 110 to press the same against the light, a handle for lifting and lowering the light, a finger grip associated therewith and means controlled by the finger grip for shifting the guides in the opposite direction. 115

6. In a window construction, a vertically movable light, a casing including a frame to receive the light when the light is raised which has a sill adapted to support the light in said frame, channels at opposite sides of the sill to guide the light and a laterally yieldable connection between the channels. 120

7. In a window construction, a vertically movable light, a casing including a frame to receive the light when the light is raised which has a sill adapted to support the light in said frame, channels at opposite sides of the sill to guide the light, a flange of one channel extending and integrally connecting with the corresponding flange of the op- 125 130

posed channel to provide a laterally yieldable connection.

8. In a window construction, a vertically movable light, a casing including a frame to receive the light when the light is raised which has a sill adapted to support the light in said frame, pivoted angle bars at opposite sides of the sill presenting a flange to one side of the light to guide the same, an angle bar having a flange overlapping the other flanges of said pivoted bars and connected thereto for diagonal movement whereby to provide spreadable channel guides, said overlapping flange being cut away adjacent the sill whereby the other flange provides a yieldable connection between the guides, and means for moving said latter angle bar.

9. In a window construction, a vertically movable light, a casing including a frame to receive the light when the light is raised which has a sill adapted to support the light in said frame, a resilient member adjacent the sill having opposed diagonal guiding surfaces and an offset follower carried by said light adapted to coöperate with said surfaces.

10. In a window construction, a vertically movable light, a casing including a frame to receive the light when the light is raised which has a sill adapted to support the light in said frame, a member adjacent the sill having opposed diagonal guiding surfaces and a resilient arm carried by said light having an offset follower portion for coöperation with said surfaces.

11. In a window construction, a vertically movable light, a casing including a frame to receive the window when raised which has a sill, a follower on the light, a guiding surface coöoperating with the follower to move said light laterally when raised to position the same for support by the sill and another guiding surface to draw the light back, said surfaces connecting at a point to permit the follower to pass from the former to the latter when the light is further raised above its supported position.

12. In a window construction, a vertically movable light, a casing including a frame to receive the window when raised which has a sill, a follower on the light, a guiding surface coöoperating with the follower to move said light laterally when raised to position the same for support by the sill and another guiding surface to draw the light back, said surfaces connecting at a point to permit the follower to pass from the former to the latter when the light is further raised above its supported position, said follower being resiliently mounted to effect automatic movement of the same to said latter surface.

13. In a window construction, a vertically movable light, a casing including a frame to receive the window when raised which has a

sill, a follower on the light, a member having a guiding surface coöoperating with the follower to move said light laterally when raised to position the same for support by the sill and another guiding surface to draw the light back, said surfaces connecting at a point to permit the follower to pass from the former to the latter when the light is further raised above its supported position, said member being resiliently mounted to effect automatic movement of said latter surface beneath the follower.

14. In a window construction, a vertically movable light, a casing including a frame to receive the light when the light is raised which has a sill adapted to support the light in said frame, guides for the light above and below the sill, means for resiliently alining the same and means effective on lifting of the light to press the edge over said sill against the resistance of said means.

15. In a window construction, a vertically movable light, a casing including a frame to receive the light when the light is raised which has a sill adapted to support the light in said frame, guides for the light above and below the sill, means for resiliently alining the same, means including a diagonal guiding surface and a coöperating follower to press the edge of the light over said sill against the resistance of said means on lifting of the light, and a guiding surface for withdrawing the light, realinement of said guides on continued lifting of the light causing said follower to move into position to coöperate with said latter surface.

16. In a window construction a vertically movable light, a casing including a frame to receive the light when raised which has a sill to support the light in the frame, guides for the light pivoted to swing therewith as the light is moved to and from the sill and resiliently urged to off position, means including a diagonal guiding surface and a coöperating follower to press the edge of the light over the sill on lifting of the light, a guiding surface for withdrawing said light, the resilient action of the guides on continued lifting of the light causing the follower to move into position to coöperate with said latter surface.

17. In a window construction a vertically movable light, a casing having a sill to support the light, means for lifting the light, means for moving it laterally on and off from the sill and channel guides receiving the edges of the light shiftable with the light in its lateral movement.

18. In a window construction a vertically movable light, a casing having a sill to support the light, means for lifting the light, means for moving it laterally on and off from the sill, expansible channel guides normally gripping the edges of the light and shiftable therewith in its lateral movement

and means associated with said lifting means for expanding the guides.

19. In a window construction a casing having a sill to support a light, a vertically movable light shiftable laterally to and from said sill, means for lifting the light, expansible channel guides normally gripping the edges

of the light and shiftable therewith in its lateral movement and means associated with said lifting means for expanding the guides. ¹⁰

In testimony whereof I have signed my name to this specification.

DAVID BOURQUE.
